ATTORNEY.

UNITED STATES PATENT OFFICE.

MILLARD H. GOULD, OF PITTSBURGH, PENNSYLVANIA.

CLAMP.

1,240,966.

Specification of Letters Patent. Patented Sept. 25, 1917.

Application filed January 13, 1916. Serial No. 71,903.

To all whom it may concern:

Be it known that MILLARD H. GOULD, a citizen of the United States, residing at Pittsburgh, in the county of Allegheny and 5 State of Pennsylvania, has invented certain new and useful Improvements in Clamps, of which the following is a specification.

The present invention relates to improvements in clamps, for attaching the end of a 10 wire rope, cable or chain to a metal or wood block such as is commonly used in all kinds of construction work. The invention has for its object provision of a strong, durable clamp of the eccentric type and of simple 15 construction and which has a "knock down" feature which expedites the attachment of the end of a stiff wire cable to any object such as a steel or wood block.

Another feature of the invention is its 20 convenient shape which enables the clamp to be placed between a series of ropes which are operating in a block without disarrangement of their respective lines of action and operation.

Still another feature of the present invention resides in the design of the head or eye of the clamp with relation to the position of the eccentric sheave forming part of the clamp, which is such that the line of 25 pull of a cable attached to the clamp is in a direct line with the head or eye portion of the clamp thus tending to avert cross strains in the clamp body as will be more fully set forth hereinafter.

In the accompanying drawings I have 30 illustrated one complete example of the physical embodiment of my invention constructed according to the best mode I have so far devised for the practical application 35 of the principles of the invention.

Figure 1 is a vertical side view of the clamp showing a wire rope just after being placed in the clamp and with all attachments in place.

40 Fig. 2 is a vertical end view of the same.

Fig. 3 is a sectional view on line 1—1 of Fig. 1.

Fig. 4 is a central sectional view of the device showing the wire rope in place and 45 the eccentric sheave in action holding the rope firmly within the clamp.

Fig. 5 is an end view of a steel block with the clamp in position and holding the end of one of the cables.

Fig. 6 is an enlarged detail end view of 55 the eccentric sheave used.

Fig. 7 is a side view of same.

Fig. 8 is an enlarged detail end view of a portion of one of the downwardly extending arms of the clamp similar to that shown 60 in Fig. 2.

Fig. 9 is an enlarged detail side view of the central axle of the clamp with its attachments.

Fig. 10 is an enlarged end view of the 65 same taken from the left of Fig. 9.

In the preferred embodiment of my invention as shown in the drawings, I utilize a casting 1 having an eye portion 2, downwardly projecting arms 3 and 4 which for 70 purposes of attaining additional strength are enlarged somewhat at 5 and 6 of Fig. 4. On the sides of casting 1 are located plates 7 and 8 which slide over pins 9, 10, 11 and 12. 11 and 12 are located directly opposite 75 to 9 and 10 as shown in Fig. 8. The pins 9 and 10, etc. are screw threaded into the body 1 of the clamp and are "pilot-ended" or bevel nosed as shown at 13 and 14 Fig. 8 to enable quick entry of said pins into their 80 respective complementary holes in plates 7 and 8. This is an important feature as will be shown hereinafter.

The two plates 7 and 8 carry an axle 15 which in turn supports the eccentric sheave 85 16. The axle has a "pilot-end" 17 Fig. 9 for easy entry through the side plates 7 and 8. The whole device is then held in assembled position by means of a locking key 18 which passes through the axle 15 and in turn 90 18 is held against disengagement by means of a cotter pin 19. It will be clearly seen that when locking key 18 is in position it will hold plates 7 and 8 against the sides 20 and 21 of casting 1 and hence the pins 95 9, 10, 11 and 12 will act as abutments for said plates 7 and 8.

The eccentric sheave 16 as shown clearly in Figs. 6 and 7 has a hole 22 which is eccentrically placed in the body 23 of the 100 sheave, said hole terminating in two raised bosses 24 and 25 formed integral with the sheave body. Also the eccentric sheave has a series of grooves 26, 26 which are made to conform with the exterior strands of a 105 wire rope such as shown in Figs. 1 and 2 thereby increasing the friction pull of the sheave. It will be understood that any other

form of indentation in the surface of the sheave other than 26 may be used such as a suitable indentation for a chain or other form of power line.

5 In use the clamp is placed in position as shown in Fig. 5; one of the bolts 27 of the block 28 is passed through the eye 2 of the clamp 1. The clamp is by this arrangement placed between all of the ascending and descending ropes 29, 30, 31 and 32 in an out of the way position and so as not to interfere with the active operations of the block 28 or of the ropes attached thereto. The end of rope 33 is attached to the clamp 1, as follows:—The cotter pin 19 and locking key 18 are removed. Plate 7 can now be instantly removed from the clamp 1. Eccentric sheave 16 can then be moved sufficiently outward to allow the stiff wire cable end 35 10 to be wrapped around same. The eccentric sheave and rope 35 can now be inserted in the cavity 36 of the clamp 1 and the side plate 7 can be slid over the "pilot nosed" pins 9 and 10 and axle 15 and the locking key 18 and cotter pin 19 then inserted and the whole clamp thus locked ready for the cam action of the sheave 16 to take place. This cam action takes place as soon as the end 36 is put under tension either in the 15 block or by any other suitable method.

As seen in Fig. 4 the sheave 16 being eccentric with reference to the axle 15 the rope is jammed between the wall of the cavity 36 and the face 37 of the sheave 16 and the 20 more tension brought on 36 in a downward direction the more secure is the cam or jamming action of the sheave as is readily seen.

It will be noted that as the end 35 of a 25 wire cable is usually very stiff and offers great resistance to being curved or bent, that an arrangement of clamp which has what may be called a quick "knock-down" feature is very essential. Otherwise it would 30 be next to impossible to insert the end 35 through the clamp. It will be further noticed in this connection that the "pilot-nosed" features before described in connection with the pins 9, 10, 11 and 12 and 35 axle 15 are also essential because exact alinement of the holes in the plates 7 and 8 with pins 9 and 10 and axle 15 thereby becomes unnecessary as the plates 7 and 8 can be hit with a hammer and driven or pried 40 "home" on said pins and axle and the stiff-

ness or stubbornness of the wire cable thus overcome with force. An additional feature is the strengthening of the clamp body at points 5 and 6 where it will be seen the reaction of the load on the cable is resisted 45 by the shear on the pins 9, 10, 11 and 12 and that there may be a good body of material into which said pins fasten, the enlargements to the clamp body are made at these points as shown. 50

Another important feature is the shape of the clamp which is so devised that when the strain is applied on 33 Fig. 5 the "line of action" of said strain will be along line 55 2—2 and in a straight line with the eye portion 2 of the clamp thus avoiding eccentric stress in the body portion 38 and providing for an almost direct pull on the eye portion 2 of the clamp. This is at once seen to be a very desirable feature. 75

Having thus fully described my invention, what I claim and desire to secure by Letters Patent is:—

1. In a line clamp in combination, a body portion having an eye, curved downwardly 80 projecting arms, integral with said body portion, pins on said arms, side plates adapted to engage on said pins, an axle mounted in said plates, and an eccentric sheave on said axle.

2. A line clamp comprising a body portion having an eye, downwardly curved arms formed on said body, an eccentric sheave adapted to be received between said arms, an axle for said sheave, removable 90 side plates and coöperating means on said side plates and said arms and said axle whereby the side plates may be readily positioned on said arms and axle.

3. A line clamp comprising a body portion having an eye, downwardly curved arms formed on said body, an eccentric sheave adapted to be received between said arms, said sheave being in such relation to the body portion of the clamp that the line 100 of pull of a cable inserted in said sheave will be in a direct line with the center of said head or eye portion of the clamp body.

In testimony whereof, I hereby affix my 105 signature, in the presence of two witnesses.

MILLARD H. GOULD.
